TELECOMMUNICATION SYSTEM EMPLOYING VOICE FREQUENCY CURRENT FOR SELECTIVE SIGNALING

Martinus den Hertog, Antwerp, Belgium, and Esmond P. G. Wright, London, England, assignors to International Standard Electric Corporation, New York, N. Y., a corporation of Delaware

Application May 8, 1943, Serial No. 486,274
In Great Britain June 11, 1940

3 Claims. (Cl. 179—18)

1

The present invention relates to alternating current communication systems, (e. g. telephone systems) employing voice frequency current for selective signaling (which will be referred to herein as dialing) and supervisory signaling.

An object of the invention is to provide means for switching the forward alternating current signaling circuit over from the "dialing" condition to the "communication" condition.

According to the invention the forward circuit is switched over from the "dialing" condition to the "communication" condition in response to a voice frequency signal transmitted back from a subsequent stage in the connection.

Embodiments of the invention will now be described by way of example, reference being made to the accompanying drawings comprising Figs. 1, 2, 2a and 2b.

Fig. 1 is a schematic diagram showing the layout of part of an alternating current communication system (e. g. telephone system) in which connections are set up over machine switching apparatus.

Figs. 2 and 2a in conjunction constitute a circuit diagram of apparatus employed at the incoming end of a toll line.

Figs. 2 and 2b in conjunction constitute an alternative circuit diagram of apparatus employed at the incoming end of a toll line.

Fig. 1 shows diagrammatically a known layout of a telecommunication (e. g. telephone) exchange network employing the Rotary system of automatic switching. This network comprises three exchanges X, Y and Z. Exchanges X and Y are connected by toll lines TL1 terminated at their ends in toll line circuits TC1 and TC2 whilst exchanges Y and Z are connected by toll lines TL2 terminated at their ends in toll line circuits TC3 and TC4.

The apparatus in exchange X includes a finder F1 linked to a group selector GS1 over a connecting circuit CC1 which is associated with a register RG1 over non-numerical switches S1. Similar apparatus is provided in exchanges Y and Z, the general operation of these registers and switches being well-known.

It will first be assumed that a connection is to be set up from the subscriber's station A connected to exchange X to the subscriber's station B connected to the exchange Y. The subscriber at A lifts his receiver and on receiving dial tone he dials the number of the station B. The code and numerical digits dialed by the calling subscriber at A are all registered in the register RG1 which retransmits them as and when required for

extending the connection over the appropriate numerical switches in succession. The code digits stored by the register RG1 are translated to provide the routing digit (or digits) necessary to control the selection (or selections) to reach the required terminating exchange, whilst the numerical digits necessary to select the desired line at the terminating exchange are transmitted by the register RG1 unchanged. When the selector GS1 has been set in accordance with the first routing digit from the register RG1 it proceeds to hunt over the toll lines TL1 for an idle line. The register RG1 then transmits the second routing digit which is received by the incoming toll line circuit TC2.

The circuit TC2 upon recognizing that the call is to terminate at the exchange Y, causes the register RG2 to be connected up over the switches F2, S2. The register RG2 sends back to the register RG1 a "proceed to dial" signal whereupon the register RG1 transmits all the numerical stored digits to the register RG2. When the register RG2 has received all the digits it sends back over the line TL1 an "end of selection" signal. The register RG1 responds to this signal and thereupon releases itself and causes the speech circuit at the exchange to be switched through. The register RG2 then proceeds to control the setting of the group selectors GS2, GS3 and the final selector FS1 to connect up the line leading to the substation B. When the called subscriber answers, an "answer" signal is sent from exchange Y to exchange X to effect a metering or like operation.

It will now be assumed that it is desired to extend a connection from substation A via the tandem exchange Y to a substation C connected to the exchange Z. The operations which take place are the same as those already described up to the selection of an idle toll line TL1 terminating in a toll line circuit TC2. The second routing digit, however, in this case is different and causes the circuit TC2 to start up a finder F3 in place of the finder F2 so as to cause the circuit TC2 to be connected over the finder F3 and the outgoing toll line circuit TC3 to an idle toll line TL2 terminating in an incoming toll line circuit TC4 at exchange Z. The circuit TC4 then sends back a "proceed to dial" signal which is received by the register RG1 and causes it to send the next routing digit, which is received by the circuit TC4.

The circuit TC4 upon recognizing that the call is to terminate at the exchange Z causes the register RG3 to be connected up over the switches

F4, S3. The register TG3 sends back a "proceed to dial" signal which is repeated at the tandem exchange Y and received by the register RG1. The register RG1 thereupon transmits all the numerical stored digits to the register RG3. When the register RG3 has received all the numerical digits it sends back an "end of selection" signal. The register RG1 responds to this signal and thereupon releases itself and causes the speech circuit at the exchange X to be switched through. The register RG3 then proceeds to control the setting of the group-selectors GS4, GS5 and the final selector FS2 to connect up the line leading to the substation C. If the call is to be routed through the exchange Z to a further exchange, the finder F5 is set in motion in place of the finder F4 and the call is routed over the outgoing toll line circuit TC5.

In systems having switching layouts similar to that of Fig. 1, it has been found possible and consequently convenient, to make the "proceed to dial" signal, the "end of selection" signal and the "answer" signal the same; in the particular example chosen they all consist of a short interruption of the backward loop.

It has been possible hitherto to make all these signals the same for the reason that the equipment at the originating exchange has been able to discriminate between them because of the different conditions existing at the originating exchange when they are received. The register RG1 has been able to recognize by its own condition whether the signal represents a "proceed to dial" signal or the "end of selection" signal; and the "answer" signal is not received by the register RG1 but by the connecting circuit CC1. It is necessary to ensure that the "end of selection" signal is received by the register RG1 within a predetermined fixed period of time from the transmission of the last digit, because otherwise there may be a danger of the signal being lost or interfered with due to the action of the calling subscriber; e. g. due to the dialing of an extra digit. The impulses hitherto employed in systems having switching layouts similar to that of Fig. 1 having been D. C. impulses or 50-cycle A. C. impulses or a combination thereof, e. g. the toll line TL1 may be operated on D. C. impulses and the toll line TL2 may be operated with 50-cycle A. C. impulses.

Various difficulties arise when it is desired to employ impulses of alternating current having a frequency in the voice frequency range, and to transmit these forward over the toll line TL1 or TL2 for dialing and backwards for supervisory signaling. The toll line circuits TC1, TC2, TC3, TC4 are in this case modified to convert the selective direct current impulses into voice frequency impulses at the outgoing end of the toll line and vice versa at the incoming end of the toll line. It is necessary, however, that immediately after all the voice frequency dialing impulses have been transmitted over TL1 and TL2, the circuits TC2 and TC4 must be rendered insensitive to the voice frequency signals in order to protect the circuit from interference due to speech, line noises, room noises, or due to the action of echo suppressors or other apparatus associated with the circuit.

It will be appreciated that the changes made to the circuits TC1, TC2, TC3, TC4 should be as small as possible and that they shall not require any changes in other portions of the equipment. The register RG1 will still be capable of distinguishing between "proceed to dial" and "end

of selection" signals as before but it is not possible to communicate this information from the register RG1 to the circuit TC1 without making extensive changes in the existing register RG1 and providing a path for sending appropriate signals from the register RG1 to the circuit TC1. Unless modifications are made to the supervisory signals, therefore, the circuit TC1 will receive an indefinite number of "proceed to dial" signals, followed by an "end of selection" signal, followed by an "answer" signal. It is only to the "end of selection" that the circuit TC1 has to respond, but it has no means for telling when this signal is received unless according to the invention it is distinguished in some way from the "proceed to dial" signals.

As has already been pointed out, it is necessary that the "end of selection" signal should reach the originating register RG1 without delay and it is, therefore, undesirable that the "proceed to dial" and "end of selection" signals which reach the incoming circuit TC2 should be subjected to an examination before re-transmission for the purpose of determining which is the "end of selection" signal. It is, therefore, arranged according to the present invention that the "end of selection" signal will be transmitted back from TC2 in precisely the same form as the "proceed to dial" signals but that subsequent discrimination made by the circuit TC2 will cause the transmission of a special signal immediately following the "proceed to dial" signal. The outgoing circuit TC1 will recognize this special signal and in response thereto it will cause the forward impulsion circuit to be disconnected and the forward speech circuit to be connected in its place.

One method of voice frequency signaling now in use utilizes currents of two voice frequencies (e. g. 600 cycles and 750 cycles) connected to the line simultaneously for use as a prefix signal which will prepare the receiver for the reception of a short impulse of a single frequency. These prefixed signals are particularly necessary after speech has commenced with the consequent likelihood of interfering voice frequency currents. Before the speech period, single frequencies may be used without danger, and it is proposed in accordance with the present invention that the "proceed to dial" signals shall each be transmitted over the toll lines TL1, TL2, as an impulse of a single frequency (e. g. 750 cycles). The "end of selection" signal is subsequently transmitted as an impulse of the same single frequency followed by the aforesaid "special signal" consisting of two voice frequencies (e. g. 600 cycles and 750 cycles) simultaneously. Suitable arrangements for transmitting these signals will now be described with reference to Figs. 2, 2a and 2b. The first arrangement employs the circuit formed by Figs. 2 and 2a taken in combination whilst the second arrangement employs the circuit formed by Figs. 2 and 2b taken in combination.

The first arrangement (Figs. 2 and 2a) is based upon the fact that routing selection is followed by the backward transmission of a "proceed to dial" signal so that impulses transmitted from the originating register RG1 only arrive when the next register is ready to receive them. When, however, the terminating exchange is reached, the remaining digits are transmitted to the terminating register without intervening selection processes and accordingly without intervening "proceed to dial" signals. It follows that if the incoming terminating toll line circuit TC4 records the fact that two digits pass in the forward direc-

tion without an intervening "proceed to dial" signal, then the next signal in the backward direction will be an "end of selection" signal. On the other hand, the switching arrangements may be such that certain selections to operators or special service positions are carried out by the transmission of only one numerical selection and, in consequence, the circuit TC4 is powerless to make the necessary discrimination. It may be possible to avoid this difficulty by modifying the switching layout to ensure that there are at least two numerical selections for every type of connection.

If this is not possible or desirable, use may be made of the second arrangement comprising Figs. 2 and 2b, to be described later.

Referring now to Figs. 2 and 2a, voice frequency impulses received over the toll line TL1 are repeated over the outgoing speaking leads as direct current impulses.

For the sake of simplicity a relay A is shown to respond to the voice frequency impulses received over TL1, but it should be understood that these impulses are preferably received by a thermionic valve circuit, a relay similar to the relay A being operated from the output of the valve circuit. When the line TL1 is taken into use, relay A is operated by a pulse of current over the line and causes the obvious operation of the relay B which locks up over contact b1 until the connection is released. The contact b6 closes the forward loop circuit and the relay G operates when this loop circuit is complete, closing at g1 a circuit for the relay D over contacts b2, j2 and g1. The contact d1 closes the obvious circuit for the relay E which locks over contact e1. Contacts d2 and d3 change over the circuit of relay A whilst contacts e2 and e3 prepare a circuit for the transmission of backward impulses. The first series of forward impulses transmitted over the line TL1 causes corresponding intermittent operation of the relay A, and the contact a2 repeats the impulses over the outgoing D. C. circuit, the short circuit at e4 having been removed. The contacts a3 maintain the relay G operated during the impulsive process.

Relay A also causes the operation of the relay C through front contacts a4 and the back contacts h4. The operation of the relay C closes the obvious circuit for relay H, which locks. Relay C has, however, provided a locking circuit for itself at contact c2 and, being slow to release, remains operated throughout the digit. Subsequently relay B releases, but relay H remains operated, being held through contacts d4 and h5.

When the consequent selection has been completed a "proceed to dial" signal, consisting of a momentary opening of the backward loop causes the momentary release of the relay G. Relay G opens the circuit of relay D which releases and at contacts d2, d3 connects a voice frequency (750 cycles) impulse to the line TL1. The release of relay D also causes the release of relay H. At the end of the "proceed to dial" signal, relay G re-operates and relay D also re-operates. The next train of impulses causes the re-operation of the relays C and H and the subsequent release of C at the end of the train. If this next train of impulses is immediately followed by a backward signal and the consequent release of relay G, the circuit TC2 will recognize this backward signal as another "proceed to dial" signal and the signal will be repeated back in the same manner as before. If, however, this next train of impulses is not followed by the release of relay G but is followed by a further train of impulses, the circuit TC2 recognizes that routing selection

has been completed and that the next backward signal will be the "end of selection" signal. When two successive trains of impulses are received without an intervening release of relay G, the first impulse of the second of these trains will close a circuit through contacts a4, c2 and h3 for relay J which is provided with a locking contact j1. When the next backward signal (which must be the "end of selection" signal) is received relay G releases D which immediately connects a 750 cycle impulse back over the line TL1.

It will be noted that in these circumstances, the re-operation of relay G at the end of the signal cannot cause the re-operation of relay D because the circuit of relay D is now held open at contact j2. Due to the release of relay D, relay H releases and connects a second frequency (600 cycles) to the line TL1 over contacts h1, h2 and contacts h1, h2 and contacts j3, j4. Relay H also opens the circuit of relay J but this latter relay, being slow to release, remains operated for a period during which the two frequencies are sent back over the line to constitute the aforesaid "special signal." When relay J releases, the circuit is reclosed for the relay D which re-operates. When the answer signal is received relay G releases momentarily whereupon relay D releases momentarily and connects a momentary pulse of voice frequency current (750 cycles) back over the line TL1.

Figs. 2 and 2b in combination show an alternative arrangement for use when it is found impossible to obtain a minimum of two numerical selections. This alternative arrangement contemplates a modification to the terminating register RG3 so that it will transmit two backward impulses for the "end of selection" signal the second following the first with a relatively small delay. If such impulses are suitably spaced, they will pass through all the D. C. and 50-cycle links in a built-up connection because they may be considered as two closely spaced "proceed to dial" signals.

The operation of relay G on seizure causes the operation of relays D and E as already explained. The receipt of a "proceed to dial" signal (a single interruption of the backward loop) causes the momentary release of relay G, and the consequent operation of relay C over contacts g2 and e5 and the release of relay D which transmits a voice frequency impulse (750 cycles) over the line TL. On re-operating, relay G closes a circuit for the relay H over contacts g2, c1 and j5. Relay C is slow to release and relay H is maintained operated for the release period of relay C. In the case of an "end of selection" signal (a double interruption of the backward loop) the first interruption causes a voice frequency impulse (750 cycles) to be transmitted as just described. The second interruption causes relay G to release a second time before relay H is restored; relay J operates and locks. The operation of the relay J causes the release of relay H, and the connection of a second frequency (600 cycles) to the line TL1, as already described. Relay H at contact h3 opens the circuit of the relay C which, on release, opens the circuit of relay J; the slow-release time of relay J controlling the duration of the impulse of current of the two frequencies simultaneously. On the release of relay J, the relay D re-operates in preparation for the transmission of the answer signal.

In the case of a tandem call from subscriber A to subscriber C via exchange Y, the circuit TC2 operates in the manner described above in the

case of the first "proceed to dial" signal. The subsequent "proceed to dial" signal is sent back from the register RG3 and causes the circuit TC4 to operate in a similar manner to the circuit TC2 and transmit back over the line TL2 a voice frequency impulse which passes through the circuits at the exchange Y and over the line TL1 to exchange X. The "end of selection" signal from the register RG3 is converted into a voice frequency signal in the circuit TC4 and transmitted back to exchange X in this form as will be readily understood from the preceding description.

What is claimed is:

1. In an alternating current communication system, a plurality of exchanges, a plurality of lines terminating at said exchanges, means including trunk lines and a series of stages of selectors at said exchanges for first selecting trunks and selectors to build up a connection between a calling line at one exchange and a called line at a second exchange and then establish communication over said connection, a current source, means for sending from said source voice frequency selective and supervisory signals from one exchange to another for controlling the building up of the connection, including supervisory signal consisting of a single direct current impulse and another kind consisting of a double direct current impulse, means at one selector stage responsive to a voice frequency signal, and means for transmitting back the last-mentioned signal from a subsequent selector stage in the connection for establishing the communication over the connection.

2. In an alternating current communication system, a plurality of exchanges, a plurality of lines terminating at said exchanges, means including trunk lines and a series of stages of selectors at said exchanges for first selecting trunks and selectors to build up a connection between a calling line at one exchange and a called line at a second exchange and then establish communication over said connection, a current source, means for sending from said source voice frequency selective and supervisory signals from one exchange to another for controlling the building up of the connection, means responsive to one kind of supervisory signal to transmit back a single voice frequency and to another kind of

supervisory signal to transmit back two voice frequencies, means at one selector stage responsive to a voice frequency signal and means for transmitting back the last mentioned signal from a subsequent selector stage in the connection for establishing the communication over the connection.

3. In an alternating current communication system, a plurality of exchanges, a plurality of lines terminating at said exchanges, means including trunk lines and a series of stages of selectors at said exchanges for first selecting trunks and selectors to build up a connection between a calling line at one exchange and a called line at a second exchange and then establish communication over said connection, a current source, means for sending from said source voice frequency selective and supervisory signals from one exchange to another for controlling the building up of the connection, means responsive to one kind of supervisory signal to transmit back a single voice frequency and to another kind of supervisory signal to transmit back two voice frequencies, means for changing the voice frequency signal transmitted back upon the receipt at said subsequent stage of two successive trains of selective signals without an intervening supervisory signal, means at one selector stage responsive to a voice frequency signal and means for transmitting back the last mentioned signal from a subsequent selector stage in the connection for establishing the communication over the connection.
